SHINGLE

Lawrence R. Clapp, Woodbury, Conn.; Helen Tilge Clapp, administratrix of said Lawrence R. Clapp, deceased, assignor to The New Haven Copper Company, Seymour, Conn., a corporation of Connecticut

Application November 25, 1936, Serial No. 112,626

6 Claims. (Cl. 108—17)

The invention relates to roof or surface coverings and, more particularly, to such coverings known in the art as shingles.

In Guiterman Patent No. 1,971,932, dated 5 August 28, 1934, a roof covering is shown made up of flat, thin, metal shingles having their lower weather edges turned up to provide flanges of sufficient height to impart the appearance of thickness to the shingle. In Guiterman Patent 10 No. 2,117,092, granted May 10, 1938, the shingle is corrugated longitudinally to enhance its beauty and effect, to strengthen the shingle and to permit it to be bent about a longitudinal axis so that it may be used as a hip shingle.

15 The present invention relates to the type of shingle disclosed in the above mentioned patent and application. According to the invention, the lower upstanding flange or toe roll is provided with a flat lying flange extension for strengthening the shingle and for obtaining other advantages. The sides of the shingle are notched to provide holding down tabs under which the flat lying flange extension of the shingles in the upper courses are inserted for holding down the weather 20 ends of the shingles. The upstanding flanges located at the lower weather edges of the shingles may be spaced from the extreme edges of the shingles by different amounts to obtain a random effect. As the total length of the shingle remains 25 the same, the variable spacing of the upstanding flanges provides toe flanges of variable lengths. If desired, the shingles, although having a generally rectangular configuration, may have their side edges converge slightly toward the top of 30 the shingle to save material.

35 The invention also consists in certain new and original features of construction and combination of parts hereinafter set forth and claimed.

Although the novel features which are believed 40 to be characteristic of this invention will be particularly pointed out in the claims appended hereto, the invention itself, as to its objects and advantages, and the manner in which it may be carried out, may be better understood by referring 45 to the following description taken in connection with the accompanying drawing forming a part thereof, in which

Fig. 1 is a perspective of a roof covered with the type of shingle according to the invention;

50 Fig. 2 is a perspective of an individual shingle;

Fig. 3 represents diagrammatically three courses of shingles showing how they are laid;

Fig. 4 is a vertical section through the lower part of the roof covered with shingles according 55 to the invention.

In the following description and in the claims, various details will be identified by specific names for convenience, but they are intended to be as generic in their application as the art will permit.

Like reference characters denote like parts in 5 the several figures of the drawing.

In the drawing accompanying and forming part of this specification, certain specific disclosure of the invention is made for purposes of explanation, but it will be understood that the 10 details may be modified in various respects without departure from the broad aspect of the invention.

Referring now to the drawing and, more particularly, to Fig. 2, the shingle comprises a generally rectangular body 10 having an upper edge 11, a lower edge 12 and side edges 13 and 14. The shingle may be of corrugated metal or other sheet material and is crimped or corrugated with the corrugations running lengthwise of the shingle for strengthening the shingle and to permit bending for use as a hip or ridge shingle, as will be explained hereinafter. The shingle may be made of any of the common metals ordinarily used for roofing, such as copper, zinc, etc. The side edges 13 and 14 may converge slightly from the lower edge to the upper edge of the shingle for the purpose of saving metal without substantially affecting the covering or protection offered by the 15 shingle.

The lower weather edge of the shingle is bent upwardly and then downwardly to provide a V-shaped toe roll or flange indicated by 15, the edge then being further bent to form the lower toe flange 16. The side edges of the shingle are provided with diagonally cut slits forming tabs 17, under which the toe flanges 16 of the shingles in the adjoining upper courses are inserted, as will be explained more in detail.

To lay a roof with these shingles, the roof indicated by 20 in Fig. 4, is first prepared in the usual way, as for laying wooden shingles for example. The lower edge of the roof may be provided with a strip of continuous sheet flashing, indicated by 21, this flashing being bent 45 down around the lower edge of the roof, as indicated, if desired. The roof may also be covered with an underlying sheet of insulating material 22, if desired, or this insulating sheet may be omitted.

The first course indicated by A is then laid, the shingles being spaced side by side in a manner similar to wooden shingles. The adjoining shingles may touch each other or they may be spaced apart, as illustrated in Fig. 3. This row 50

is secured to the roof by driving nails 26 through the shingles into the roof. Two nails may be used for each shingle and these nails are placed below the upper edge of the shingle as far as possible, 5 so long as these nails are covered by the next course of shingles.

To assist in holding down the butt ends of the shingles in the first course, the lower flange 12 may be bent downwardly. Course A shows the 10 toe flanges thus bent. Nails 25 driven through the toe flanges into the roof 20 hold the weather edges down securely.

In course A, the upstanding flanges or toe rolls 15 may be aligned or not according to the effect 15 desired. If the toe rolls 15 are all aligned, it is obvious that shingles having the same size toe flanges may be used for this bottom course. If the random effect is desired, shingles having different size toe flanges are used, in which case it is 20 obvious that only part of the toe flange 12 of the larger size toe flanges will be bent down as illustrated, for example, by shingle 23 in row A.

In case it is not desired to bend down the toe flanges 12, special shingles may be made in the 25 factory having the toe flanges bent down so that the lower row of shingles may be applied without distorting the toe flanges on the job.

After the first course A is laid in the manner described, course B is laid. In this course the toe 30 flanges 12 are inserted under the tabs 17 of the shingles in course A and nails 27 are driven through the shingle bodies into the roof in a manner similar to course A. Care should be taken, however, that the spaces between shingles in 35 course B are staggered with respect to the spaces in course A. The toe flanges 12 effectively hold down the weather edges of the shingles in course B and perform the same function as the depending flanges in course A.

40 Course C is laid in a manner similar to course B with the toe flanges 12 tucked under the tabs 17 and with the spaces between shingles staggered with respect to the spaces between shingles in course B. The succeeding courses are laid in 45 a similar manner until the top of the roof is reached.

The ridge of the roof may be covered by a 45 course of shingles indicated by X. These shingles may be identical with the shingles in courses B and C and are laid by bending the shingles about a line running lengthwise of the shingles, the corrugated construction permitting the upstanding flanges 15 to give or expand so that the shingles may be bent without otherwise distorting them. 50 Nails will be driven through the shingle bodies at suitable points in the body 10 of the shingle. Nails may be placed in the toe flange 12 also if desired. The shingles in the ridge course may be laid without regard to the length of toe flange 55 12 or, if desired, the length of toe flange may be the same in all the shingles. Or shingles having no toe flange 12 at all, such as disclosed in the above mentioned Guiterman application, may be used in this row.

60 The shingles may also be used to cover a hip caused by the intersection of two inclined roof planes in a manner as described in the Guiterman patent above referred to. In this case also the toe flanges 16 may be of variable length, the same 65 length, or omitted entirely, as described above in connection with the ridge shingles.

It will be noted from the above and from the drawing that all of the regular shingles (exclusive of course A and ridge or hip shingles) are of the 70 same length irrespective of the position of up-

standing flange 15 and that the tabs 17 are always at the same distance from both the lower edge 12 and upper edge 11 of the shingle irrespective of the position of the upstanding flange 15. This construction provides automatic spacing of the 5 courses with uniform overlapping between courses and yet gives a random effect similar to that obtained in ordinary wooden shingles, for example, by varying the overlap between courses. The provision of tabs 17 at a constant distance from 10 the lower edge of the shingle insures the holding down of the shingles in a uniform manner irrespective of the random effect portrayed by the upstanding flanges.

In addition to the random effect obtained by 15 the variable position of the upstanding flanges, a random effect may be obtained by changing the spacing between shingles in the same row. A random effect may also be obtained by changing the width of the several shingles to get the desired effect. Furthermore, if desired, the height 20 of the toe roll may be varied to obtain a random effect, all depending upon the architectural appearance desired.

It is obvious that the dimensions of the shingle 25 and the overlap may be varied widely as in the case of wooden shingles. For example, these shingles may have a uniform length of about fifteen inches and may run in width from seven to twelve inches. The taper of the side edges 13 and 14 30 may make the width of the shingle two inches less at the top than at the bottom. The crimping or corrugations may run, for example, four or five corrugations per inch, although a somewhat coarser pitch is indicated in Figs. 2 and 3. The 35 gage of metal may be #29 Brown & Sharpe. The lower upstanding flange may be approximately one inch wide as measured up and down the length of the shingle, and the height of this flange may be approximately seven-eighths of an inch 40 above the plane of the shingle. The tabs 17 may be placed at about six inches from the lower edge 12, thereby providing a nine inch overlap between adjacent courses and a three inch overlap between every third course.

45 Thus, a shingle construction has been disclosed which has the advantages inherent in this type of shingle. It also has certain additional advantages, as for example, the saving in metal due to the tapering of the side edges 13 and 14, 50 above described; the holding down of the butt ends of the shingle by inserting the toe flanges under the tabs of the shingles in the next lower row; the variable positioning of the upstanding flanges to give a random effect without destroying the uniform coverage and uniform laying of 55 the courses; the shingle has increased strength due to the addition of the lower toe flange which strengthens the upstanding toe roll 15. These advantages are obtained without sacrificing any 60 of the protection offered by this type of shingle against the elements and without interfering with the use of these shingles as hip shingles or ridge shingles.

The use of the additional toe flange 16 also 65 provides an additional element by which the shingle may be fastened to the roof. Nails may be driven through this flange when the shingle is used as a ridge shingle or when used in the first course of shingles. Throughout the main 70 area of the roof the overlying tabs in the shingles in the lower rows enables this flange to hold down the shingles in the overlying courses.

By the use of this shingle many beautiful architectural effects can be obtained. The corruga- 75

tions permit bending the shingles to conform to a rolling roof and the interlock between toe flange and tabs insure the holding down of the weather edge of the shingle on any shape of surface. The upstanding toe roll or edge flange 5 imparts the appearance of thickness to the shingle when viewed from a distance and yet permits the body of the shingle to lie flat against the roof for obtaining maximum protection 10 against the weather.

While certain novel features of the invention have been disclosed and are pointed out in the annexed claims, it will be understood that various omissions, substitutions and changes may be 15 made by those skilled in the art without departing from the spirit of the invention.

What is claimed is:

1. A shingle comprising a body of generally oblong conformation and made of corrugated 20 sheet metal with the corrugations running up and down, the side edges of said shingle converging slightly upwardly to save material, said body having upstanding therefrom at the lower edge thereof a flange-like portion formed by 25 bending the sheet metal upwardly and then downwardly to form an upstanding, inverted, trough-shaped flange, the metal being further bent to form a short toe flange projecting below 30 said upstanding flange and lying in substantially the same plane as said body, the side edges of 35 said body being slit downwardly and inwardly to form upwardly extending tabs to overlie the toe flanges of shingles in the next upper course. 40

2. A shingle comprising a body made of corrugated sheet material with the corrugations running lengthwise, said body having upstanding 45 therefrom at the lower edge thereof a flange-like portion formed by bending the sheet metal into an upstanding, inverted, trough-shaped flange, 50 said shingle having a toe flange projecting below said upstanding flange and lying in substantially the same plane as said body, the side edges of 55 said shingle having upwardly extending tabs to overlie the toe flanges of shingles in the next upper course.

3. In a shingled surface, a series of courses of shingles, each shingle comprising a body adapted to lie generally flat on a supporting surface and an upstanding flange at its lower edge, but spaced 60 from the lower margin of the shingle, the flanges of the several shingles being spaced at different distances from the lower margins thereof to give a random effect, the side edges of said shingles having tabs for overlying the lower edges of overlying shingles, the overall lengths of the several shingles being substantially equal and the tabs of the several shingles being located at the same distance from the lower margin of the shingles irrespective of the position of the upstanding 65 flanges.

4. In a shingled surface, a series of shingle courses each shingle being substantially rectangular and adapted to lie generally flat on a supporting surface, each shingle having its lower

edge bent upwardly and then downwardly to form a flange-like member and then bent outwardly to form a toe flange in the plane of the body of the shingle, said toe flanges in the various shingles being of variable length, said shingles each having 5 a hold down tab, the shingles in each course being spaced, the spaces between shingles of adjoining courses being staggered and the toe flanges of the shingles in the upper courses underlying the tabs of the shingles in the adjoining lower 10 courses, the overall lengths of the several shingles being substantially equal and the tabs of the several shingles being located at the same distance from the lower margin of the shingles irrespective of the position of said flange-like members. 15

5. In a shingled surface, a plurality of courses of shingles, the shingles in each course being laterally spaced, the shingles in the courses having the spaces therebetween staggered with respect 20 to the courses next above and next below, the shingles in each upper course overlapping the shingles of the next lower course and also the shingles of the lower course once removed, each shingle being formed from a metal sheet having 25 a substantially rectangular body portion with the side edges of the body portion lying substantially in the same plane as the body portion, the body portions of the shingles lying flat against the supporting surface, each shingle having upstanding 30 therefrom at the lower edge thereof a flange-like portion formed by bending the sheet metal upwardly then downwardly to form an upstanding trough-shaped flange, the metal being further bent to form a short toe flange projecting 35 below the said upstanding flange in the plane of the body of the shingle, the side edge of each shingle body being slit to form a tab, the toe flanges of the shingles in the courses above underlying the tabs of the shingles in the next lower 40 courses.

6. In a shingled surface, a plurality of courses of shingles, the shingles in each upper course overlapping the shingles of the next lower course, each shingle being formed from a metal sheet 45 having a body portion with the side edges of the body portion lying substantially in the same plane as the body portion, the body portions of the shingles lying flat against the supporting surface, each shingle having upstanding therefrom at the 50 lower edge thereof a flange-like portion formed by bending the sheet metal upwardly then downwardly to form an upstanding trough-shaped flange, the metal being further bent to form a short toe flange projecting below the said upstanding flange in the plane of the body of the shingle, the side edges of the shingles in the lower courses and the toe flanges of the shingles in the upper courses constituting sets of attaching edges, one of said attaching edges of each 55 set having a tab interlocking with the other edge of said set to hold down the shingle in the upper course.

LAWRENCE R. CLAPP.
